United States Patent Office

Des. 211,759
Patented July 23, 1968

211,759

CAMERA BODY AND CONE

Erhard M. Winkler, 17635 Juday Lake Drive,
South Bend, Ind. 46635

Filed Mar. 7, 1967, Ser. No. 6,107

Term of patent 7 years

(Cl. D61—1)

FIG. 1

FIG. 2

FIG. 3

FIG. 6

FIG. 4

FIG. 5

FIGURE 1 is a side elevational view of a camera body and cone, showing my new design, the opposite side being substantially a mirror image thereof;

FIGURE 2 is a front elevational view;

FIGURE 3 is a top plan view;

FIGURE 4 is a bottom plan view;

FIGURE 5 is a fragmentary elevational view as seen from vantage point on line 5-5 of FIGURE 2; and

FIGURE 6 is a perspective view.

The broken line showing of a conventional camera back, supporting handle, viewfinder and lens for illustrative purposes only.

I claim:

The ornamental design for a camera body and cone, substantially as shown and described.
